(57) CLAIM

The ornamental design for a glove, as shown and described.

DESCRIPTION

The broken lines shown in the figure represent portions of the article and form part of the claimed design. Portions of the glove that are not shown form no part of the claimed design. A left-hand glove is depicted in the FIGURE, it being understood that a right-hand version of the glove would be of mirror image appearance.
